UNITED STATES PATENT OFFICE.

JAMES C. SMITH, OF ELYRIA, OHIO, ASSIGNOR TO THE MACHINE PARTS COMPANY, OF ELYRIA, OHIO, A CORPORATION OF OHIO.

VELOCIPED.

1,141,278.

Specification of Letters Patent.

Patented June 1, 1915.

Application filed December 5, 1914. Serial No. 875,597.

To all whom it may concern:

Be it known that I, JAMES C. SMITH, a citizen of the United States, residing at Elyria, in the county of Lorain and State of Ohio, have invented certain new and useful Improvements in Velocipedes; and I do hereby declare the following to be a full, clear, and exact description of the invention, such as will enable others skilled in the art to which it appertains to make and use the same.

My invention relates to velocipedes, and more particularly to children's velocipedes, and has for its general object improvement in the construction of velocipedes to make them more economical, efficient and durable. I also aim to conceal and suppress many of the parts which have hitherto projected from the frame work, often causing the tearing of clothes or the bruising of the children who operate the velocipede. In my construction, the parts better support and brace each other than in the vehicles heretofore in use, while at the same time I have cheapened and strengthened the structure. In accomplishing these objects I employ parts of well known construction, and which are made upon standard machines, thereby not only accomplishing the desirable function and purposes named, but doing it with a cheaper structure.

Other objects of my invention and the invention itself will probably be better understood from a description of an embodiment of my invention.

Figure 1 is a section showing parts of an embodiment of my invention in elevation. Fig. 2 is a section taken along the line 2—2 of Fig. 1. Fig. 3 is a perspective view of the saddle block. Fig. 4 is a section through the line 4—4 of Fig. 1. Fig. 5 is a section through the line 5—5 of Fig. 1. Fig. 6 is a section through the line 6—6 of Fig. 1, and Fig. 7 is a section through the line 7—7 of Fig. 1.

Referring now to the embodiment of my invention illustrated in the drawing, at 8 is shown the large wheel of the velocipede, which is mounted upon an axle 9 journaled in a fork 10, which is connected to the frame head 37. The prongs 12 of the fork, one only of which is illustrated in the drawings, are made of channel iron, the bottom of the

channel being illustrated at 13 and the sides at 14—15. The bearing 16 for the axle 9 is held between two clamping members 17 and 18, which are connected by any suitable means, such as screws or rivets 19. The member 18 is provided with an arm 20 which fits into the channel in the prong of the fork, as illustrated in Figs. 1 and 4, and is secured thereto by suitable means, such as a rivet 21. The sides 22 of the arm 20 engage the inside walls of the channel sides, thereby holding the member 18 securely in position, so that it can be connected to the fork for all purposes by a single rivet. Any force tending to break the connection will be resisted by the walls of the channel iron. At the same time, the connection is concealed, making a neat and efficient joint.

The ends 25 of the channel rest against the top of the member 18, still further bracing the parts coupled together at this joint. The fork is pivoted to the frame 11 at 27 in a well known manner, and is connected to handle bars 28, the fork and the front wheel being controlled by the handle bars in a manner well known and understood, and which constitutes no part of my invention. Pedals 28 and pedal cranks 29 are also provided, one of each being shown in the drawing. One of the rear wheels is shown at 30; another is provided as is usual in tricycles or polycycles. I have illustrated one only because it is sufficient for the purpose of illustrating my invention. The rear axle is shown at 31 and is connected to the frame members 32, one of which only is shown. The frame members 32 are also made of channel iron, the bottom being shown at 33 and the sides at 34, 35. A connecting arm 36 is provided upon the head piece 37, being preferably integral therewith and of such shape that it fits snugly within the channels as illustrated in Fig. 7, the bottom of the channels 32 engaging the sides of the arms 36 and the sides of the channel engaging the top and bottom thereof, as illustrated in Fig. 7. The three parts are held together by suitable means, such as rivets 38.

As will clearly be seen, the connection between the frame members and the frame head is firm, neat and simple. There are no projecting parts and no complicated joints to make, and when once connected, the sides

of the channels engaging the top and bottom of the block efficiently secure the parts together.

A saddle is shown at 40, which is connected by suitable means, such as a clamp shown at 41, to a saddle post 42. A saddle post block is shown at 43, which is perforated, as shown at 44 for the saddle post. This block is so dimensioned that it fits within the channels in the same manner as the arm 36. This structure is well illustrated in Fig. 5 and shows how the saddle post is neatly and securely fastened to the frame. The block is held in the frame by suitable means, such as rivets 45. Behind the block 43 the frame members are spread apart in a manner well known in velocipedes, and at 50 a brace is provided which spans the two, connecting them together and serving as a step from which the children sometimes mount into the saddle. This brace consists preferably of a channel bar which is bent over at 51 to form a foot portion 52, which fits within the channel of the frame members, as illustrated at 53, the sides of the bar engaging the sides of the channel, likewise providing a cheap, neat and efficient connection. These parts are held together by some suitable means, such as rivets 55. It will be readily understood that the braces may be located at any suitable place, and that any number of braces may be employed connected to the frame in substantially the same manner.

The block 43 is preferably cut away at the ends, as shown at 60, 61 leaving arms 62 which extend along the inner walls of the channels, more securely holding the saddle block in position in the frame. The block 40 is perforated at 63 and 64 for the securing means 45. This block is also preferably provided with perforations 70 in the arms 62, through which rivets, bolts or other suitable means may be inserted to more firmly attach the block 43 to the frame. The block is further provided with a hole 80 for a set screw 81, to hold the post in position in the block.

I have illustrated this embodiment and these details for the purpose of explaining my invention and not that I wish to be limited thereto, as it will be clear that numerous and extensive departures may be made from both the form and details of the apparatus without departing from the spirit of the invention, the scope of which is more clearly set forth in the appended claims.

I claim:

1. In a velocipede, a pair of frame members made of channel iron with the channel portions turned inwardly, a saddle block fitting within the channels, and means for holding the frame members and saddle block together.

2. In a velocipede, the combination of wheels, a frame, a saddle, a saddle post, a saddle block perforated for the post, a pair of frame members made of channel iron, a frame head to which said members are connected at one end, said saddle post block fitting within the channels and engaging the inside walls thereof, arms on said block extending from the block within the channels, said block and arms being substantially concealed within the channels, and means to hold the channel block in the channels, said means and block serving to bind said members together.

3. In a velocipede, the combination of wheels, a frame, a saddle, a saddle post, a saddle block perforated for the post, a pair of frame members made of channel iron, a frame head to which said members are connected at one end, said saddle post block fitting within the channels and engaging the inside walls thereof, said block being protected by the channels and substantially concealed therein, and means to hold the saddle block in the channels, said means and block serving to bind said members together.

4. In a velocipede, the combination of wheels, a frame connecting the wheels together including a fork whose prongs are made of channel irons, means to connect the front wheel in the fork, including a member provided with an arm fitting within the channel iron of the fork prong and engaging the inside walls thereof, the hollow portion of the channel iron facing the wheel and means to hold said arm in said channel, the walls of the channel serving as a brace and support for said arm.

5. In a velocipede, a pair of converging frame members made of channel iron with the channel surfaces turned toward each other, a saddle block mounted within the channel portions at the point of convergence of said frame members, and means to connect said block and frame members together, said block serving to space said frame members apart.

6. In a velocipede, the combination of a pair of converging frame members made of channel iron with the channel members turned inwardly toward each other, a perforated saddle block mounted within the channels of said frame members at the point of convergence, arms on said block extending from the block along the inside of the channels and means to connect said block and frame members together, said block serving to space the members apart.

7. In a velocipede, the combination of the wheels, the fork and a pair of frame members connecting the rear wheels to the fork, said frame member being composed of a pair of converging channel irons, a saddle block mounted within the channels of said irons at the point of convergence thereof, and

means to connect said block to said frame members, said block being perforated and a saddle post mounted in the perforation in said block.

- 5 8. In a velocipede, the combination of wheels, a frame connecting the wheels together including a fork whose prongs are made of channel irons, means to secure the front wheel in the fork, including a member provided with a bearing for the front

axle, an arm on said member fitting within the channel in the fork prongs, and means to connect said arm to said fork prongs.

In witness whereof, I have signed my name in the presence of two witnesses, this 15
1st day of Dec., 1914.

JAMES C. SMITH.
